CLAIM

The ornamental design for a clog style molded plastic shoe, as shown and described.

DESCRIPTION

FIG. 1 is a left side elevation view of a clog style molded plastic shoe for a left foot showing my new design; FIG. 2 is a top plan view thereof;

FIG. 3 is a right side elevation view thereof;

FIG. 4 is a toe elevation view thereof; and,

FIG. 5 is a heel elevation view thereof; and, the mirror images of FIGS. 1-5 are views of a second embodiment for a right foot.

The surfaces of the clog style molded shoe that are not shown form no part of the claimed design.
